UNITED STATES PATENT OFFICE.

JACOB LAGOWITZ, OF NEWARK, NEW JERSEY.

IMPROVEMENT IN TRAVELING-BAGS.

Specification forming part of Letters Patent No. 123,830, dated February 20, 1872.

Specification describing an Improvement in Traveling-Bags, &c., invented by JACOB LAGOWITZ, of Newark, in the the county of Essex, and State of New Jersey.

Figure 1 is a side view of my improved traveling-bag. Fig. 2 is a detail sectional view of the same taken through the line $x x$, Fig. 1. Fig. 3 is a detail sectional view, illustrating the old construction.

Similar letters of reference indicate corresponding parts.

My invention has for its object to furnish an improved mode of making traveling-bags, &c., by means of which the cover of the frame, the cover of the bag, and the lining may all be sewed at the same time, and with a sewing-machine; and it consists in the mode of making the bag, as hereinafter more fully described.

In making traveling-bags in the old way, the edges of the cover, or the frame and the edge of the cover of the bag, were brought together upon the inside, as shown in Fig. 3, and sewed by hand. The edge of the lining was then brought over the seam thus formed and sewed down by hand, thus requiring two rows of hand-sewing all around each half of the bag.

In making a bag in accordance with my invention, the edges of the cover A of the frame B are brought together at the edge of the frame B, and turned outward. The edge of the cover

C of the bag, and the edge of the lining D are then brought together and placed upon the inner side of the edges of the frame-cover A, a narrow strip, E, of the lining D, being interposed between the edges A and the edges C D. The edges A C D E are then sewed together by a machine, and the free-edge of the strip E is pasted down over the edges of the cover C and lining D, as shown in Fig. 2.

If desired, the edge of the cover C, or of the cover C and lining D, may be placed and sewed in the manner hereinbefore described upon the outer side of the edges of the frame-cover A; but I prefer the way first described, as making a better and neater bag.

Having thus described my invention, I claim as new, and desire to secure by Letters Patent—

The mode of making traveling-bags, herein shown and described—that is to say, by overlapping the edges of the frame-cover A, the bag-cover C, the lining D, and strip E, and securing them by a single row of machine-sewing, substantially as and for the purpose herein set forth and described.

The above specification of my invention, signed by me this 27th day of December, 1871.

Witnesses: JACOB LAGOWITZ.
